(57) **CLAIM**

The ornamental design for a headlight for a vehicle, as shown and described.

DESCRIPTION

This application contains subject matter related to the following co-pending U.S. design patent applications:

Application Ser. No. 29/813,885, filed Nov. 2, 2021 and entitled "Headlight For A Vehicle";

Application Ser. No. 29/832,158, filed Mar. 25, 2022 and entitled "Headlight For A Vehicle"; and

Application Ser. No. 29/839,541, filed herewith and entitled "Motor Vehicle, Toy Replica, And/Or Other Replica".

FIG. 1 is a front view of a headlight for a vehicle according to the design;

FIG. 2 is a right, front perspective view thereof;

FIG. 3 is a left, bottom perspective view thereof;

FIG. 4 is a right side view thereof;

FIG. 5 is a left side view thereof;

FIG. 6 is a top view thereof;

FIG. 7 is a bottom view thereof; and,

FIG. 8 is a rear view thereof.
